UNITED STATES PATENT OFFICE.

SAMUEL D. McKINSTRY, OF SEATTLE, WASHINGTON.

DESIGN FOR CANDY.

51,504.

Specification for Design.

Patented Nov. 20, 1917.

Application filed August 15, 1916. Serial No. 115,088. Term of patent 3½ years.

To all whom it may concern:

Be it known that I, SAMUEL D. McKINSTRY, a citizen of the United States, residing at Seattle, in the county of King and State of Washington, have invented a new, original, and ornamental Design for Candy, of which the following is a specification, reference being had to the accompanying drawing, forming part thereof.

In the drawing, Figure 1 is a perspective view of a piece of candy showing my new design.

Fig. 2 is a side elevation of the same.

I claim:

The ornamental design for candy, as shown.

SAMUEL D. McKINSTRY.
